(57) **CLAIM**

The ornamental design for an electric cooktop, as shown and described.

DESCRIPTION

FIG. 1 is a top perspective view of an electric cooktop showing our new design according to a first embodiment; FIG. 2 is a bottom perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof;

FIG. 8 is a bottom view thereof;

FIG. 9 is a top perspective view of an electric cooktop showing our new design according to a second embodiment; FIG. 10 is a bottom perspective view thereof;

FIG. 11 is a front view thereof;

FIG. 12 is a rear view thereof;

FIG. 13 is a right side view thereof;

FIG. 14 is a left side view thereof;

FIG. 15 is a top view thereof; and,

FIG. 16 is a bottom view thereof.

The broken lines illustrates portions of the electric cooktop that form no part of the claimed design. The dot-dash lines define the bounds of the claimed design and form no part thereof. The grayscale shading indicates a contrast in appearance.

1 Claim, 16 Drawing Sheets
